UNITED STATES PATENT OFFICE.

EDWIN N. CHANDLER, OF BRAINTREE, MASSACHUSETTS.

ELECTRICALLY-HEATED STENCILING-MACHINE.

1,144,809.

Specification of Letters Patent. Patented June 29, 1915.

Application filed March 19, 1913. Serial No. 755,319.

To all whom it may concern:

Be it known that I, EDWIN N. CHANDLER, a citizen of the United States, and resident of Braintree, county of Norfolk, State of Massachusetts, have invented an Improvement in Electrically-Heated Stenciling-Machines, of which the following description, in connection with the accompanying drawings, is a specification, like letters on the drawings representing like parts.

This invention relates to stenciling machines, and more particularly to an electrically heated stenciling machine; the object of the invention being to improve and perfect machines of this type, and to provide a construction which will be simple in operation and economical to manufacture.

My improved stenciling machine includes a carrier, having a plurality of characters, such as initials, thereon, each character being arranged for operative position with a work table by a rotative movement of the carrier. Preferably the carrier is so arranged that the stenciling members held thereby may be readily detached and attached, as well as means to secure such members in an adjusted position radially with the carrier.

Also it is an important feature of my present apparatus to so arrange the electrical heater and the carrier holding the stenciling members, to insure a continual application of a uniform degree of heat to such stenciling members, even while such carrier is being moved and maintained into operative engagement with the work, or while the carrier is out of engagement with the work.

My invention also comprises means whereby the work to be operated upon may be quickly and readily clamped to the work support or table in proper position to be acted upon by any one of the stencils supported by the carrier, at the will of the operator. Furthermore, I preferably arrange the table so that the work may be adjusted while still held in its original clamped position, to any predetermined distance desired for a second or additional stenciling operation by the same or a different stencil. This predetermined spacing of successive operations on the work is preferably determined by means of a gage or scale.

The provision of an electrically heated stenciling device is, so far as I am aware, a distinct novelty in this art and my inven-

tion comprises an electrical heating means normally out of contact with the stenciling members, but held in the carrier and adjacent to said members so that the desired degree of heat may be imparted thereto at all times.

Heretofore it has been attempted to heat stenciling devices by gas or steam, but such an arrangement is very unsatisfactory, necessitating a cumbersome and expensive arrangement where a steam shaft or the like was employed; and the use of a gas flame is highly objectionable, because of the character of the work, often highly inflammable, and the danger of blackening the dies or stencils, and thereby marring the work.

By means of my invention I am enabled to obviate the objections above noted, and to provide a uniform heat at all times to the stencil members and prevent any discoloring or marring due to such application of heat. Preferably I arrange the carrier having the stencil members or dies therein to be actuated by a foot treadle and maintain the same normally out of contact with the work, by means of a suitable spring.

Other features of the invention, novel combinations of parts and details of construction, will be hereinafter more distinctly pointed out and claimed.

Referring to the drawings, Figure 1 is a front view of a stenciling apparatus, embodying my invention in a preferred form; Fig. 2 is a side view; Fig. 3 is a cross section, enlarged, on the line 3-3 of Fig. 1; Fig. 4 being an enlarged view on the line 4-4 of Fig. 2.

The apparatus is intended to be supported on the edge portion of a bench or table 1, and its frame carried by a base 2, with a forward bracket member 3, and secured to the base 2 is an upstanding arm 4, slightly overhanging the bracket 3, as indicated at 5. The head 5 carries a vertical groove in which a slide 6 is mounted, said slide having its upper portion forked, as indicated at 7, to receive the end of a lever 8, being pivotally connected thereto by a bolt 9. This lever has its other end carried loosely on a pin 10, supported through the upper forked arms of a bracket member 11, secured to the rear of the portion 4, as shown in Fig. 2. The lever 8 is pivotally connected at 12 to the head 13 of a rod 14 connected to a foot treadle (not shown) having a coiled spring 15 encircling the upper end of the rod 14.

and bearing upwardly against the head 13 and between a socket 16 formed to receive this spring in the top of the arm 4. The spring 15 normally maintains the lever 8 and slide 6 in uppermost position, as shown, and the rod 14 is connected to a suitable foot treadle, so that the lever 8 may be depressed against the tension of the spring 15 to move the slide 6 downwardly. Secured to the slide 6 by suitable screws 17 and 18 is a circular plate 19, preferably formed with a recess in the rear thereof, viewing Fig. 3, in which recess is fitted an electrical heating coil 20. This plate 19 also has a central hub 21 and a boss 22 on one side. The hub 21 is formed to project slightly to the left, viewing Fig. 3, beyond the outer surface of the plate 19, and a circular carrier 23 is formed with a central aperture to fit over the hub 21 and is loosely held in position that it may freely rotate on said hub, by a washer 24 and a headed bolt 25 with its shank 26 passing through the hub 21, and having its inner end threaded into a correspondingly tapped socket 27 in the carrier slide 6. The boss 22 formed on the plate 19 is bored to receive a plunger 28 passing therethrough and provided with a collar 29 near its inner end, and a handle 30 on the outer end, said boss 22 being counter-bored from its inner end to receive an expansible spring 31, which bears between the socket formed by said counter-boring and the collar 29 on the rod 28, tending to force the rod 28 normally toward the left, viewing Figs. 2 and 4. The carrier 23 is provided with a plurality of recesses 32 around its periphery, which are in line to register with the rod 28, so that as the carrier 23 is given a rotative movement, the rod 28 will spring into an adjacent recess 32 and hold the carrier relatively with the plate 19. The operator, upon moving the handle 30 to withdraw the rod 28 from engagement with any of said sockets 32, can then easily rotate the carrier 23 to a new position, when said carrier may again be locked as before. The carrier 23 is designed to hold a plurality of dies 33 around its periphery, and for this purpose I provide a ring 34, having a flange 35 which is secured to the carrier 23 by a plurality of screws 36 arranged about its periphery. At suitable points also, set screws 37 are provided, which will bear against the shank of the dies 33 as the same are positioned and rest upon the flange 35 (see Fig. 3). Preferably the dies 33 are so positioned about the periphery of the carrier in relation to the various recesses 32, so that as a die is in lowermost position, the carrier 17 will be locked to the plate 19 by the action of the rod 28 co-operating with a recess 32, one such recess being provided for each die carried.

The forward bracket 3 is for the purpose of positioning the machine on the edge of a

support, and also for the purpose of carrying a movable work-support or slide, being for this purpose provided with dovetailed grooves for the transverse slide 38, which slide also carries a second slide 39 having a rib 40 fitting in a groove in the top of the slide 38, and at right angles to the guideway provided in the bracket 3. This arrangement provides a convenient work support, and is in proper position underneath the slide 6 and carrier 17 so that the work to be operated upon may be positioned on the top of the slide 39, and receive the imprint of a die 33, when the rod 14 is depressed and the carrier 6 descends, the spring 15 automatically returning the slide 6 and raising the dies from the work. To facilitate manipulation of the slides 38 and 39, I attach to said slide 38 a pivoted arm 41, having a series of notches 42 of a predetermined distance apart, which notches fit over a lug 43 mounted at one side on the base 2. A spring 44 tends to hold the arm 41 within a notch 42 in engagement with the stud 43, but permits said arm to be raised and the slide moved to a second position. I also provide a spring catch 45 on the top of the work support 39, having a handle 46 to facilitate raising the same and positioning the work to be operated upon underneath the catch 45, where it is held during the further operations of the stenciling apparatus. A set screw 47, arranged as shown in Fig. 2 and passing through an elongated slot in the spring 45 permits the lateral adjustment of this spring, and secures the same to the work table. I also provide a suitable electrical connecting device 48, so that the well-known and standard type of connector may be affixed to the apparatus and supply current to the electrical heater 20 which will thus maintain the dies in a satisfactory degree of heat. In stenciling on leather or the like, heat is of particular importance in rendering the imprint of the die more permanent as well as affording an ornamental or embossing effect.

An article to be operated upon is first positioned by the attendant under the spring clip 45 on the work table 39. The carrier 23 is then rotated to bring the desired die into lowermost position, when the spring actuated rod 28 will hold the carrier in this position during the operation. The foot treadle actuating the rod 14 is then depressed, and the slide 6 reciprocated carrying the plate 19, and the die supported thereby, downwardly, until the lowermost one contacts with the work when the operator releases the treadle. The work may then be moved while still clamped, by moving the slide 38 laterally to engage another notch in the arm 41 with the stud 43, and a second die may be brought into position by rotation of the carrier 23, and the operation

repeated. In stenciling initials or the like, it is, of course, desirable to maintain a uniform distance between the impressions, and therefore the notches 42 are made uniform so that the slide 38 may be instantly and easily positioned a uniform distance for each successive stenciling operation. It is, of course, feasible, however, to move the slide 38 any desired distance as well as to actuate the slide 39 to and fro in stenciling two or more rows of characters, letters or the like. It will be readily appreciated that I have provided a stenciling apparatus which maintains the dies or characters in any desired degree of heat to facilitate the stenciling operation, and that the entire apparatus is economical to construct, simple to operate, adjustable in all respects, carrying a large range of dies or characters, and is efficient in operation, any reasonable degree of force being afforded by the leverage of a foot treadle on the actuating rod. In order to facilitate the locking of the carrier 23, I may provide the ring 34 with printed characters corresponding in number and of similar significance with those on the dies 33, which characters on the face of the ring 34 will be opposite the locking rod 28 when the die carrying the corresponding character will be in the lowermost position, as shown at 49. Thus, for example, if the die 49 has on its operative face the letter "A", then the letter "A" will appear on the ring 34 in proper position opposite the locking rod 28, so that when the carrier 23 is positioned with the die 49 in lowermost position, the carrier may be locked and operated. This arrangement affords a convenient means of enabling the operator to determine just what die is in position for use, and fa-

cilitates the easy, quick, and ready operation of the apparatus.

Having described my invention, what I claim as new and desire to secure by Letters Patent is:

1. A device of the kind described, comprising a slidable carrier, a hub rigidly secured to said carrier and supporting a plate having a recess in one face, an electrical heater carried in said recess, a die carrying plate rotatably supported by said hub and in contact with the heater containing plate throughout substantially its entire extent, a plurality of stenciling dies removably secured to said plate and all in substantially equal heat receiving position, in combination with means carried by said heater containing plate to lock the die carrying plate in rotative position to hold a selective die in work engaging position. 60

2. An electrically heated stenciling apparatus, comprising a rotatable carrier, a vertically reciprocating carrier having thereon electrical heating means, a rotatable die carrying plate with its dies removably secured to its periphery, a locking member on the side of said rotatable die carrying plate to hold said plate with a selective die in lowermost position to engage the work, and an indicator on the plate for each die 70 in position adjacent said lock to indicate which die is in work engaging position on the lowermost portion of said plate. 65

In testimony whereof, I have signed my name to this specification, in the presence of 75 two subscribing witnesses.

EDWIN N. CHANDLER.
